WASHING MACHINE

Filed Aug. 17, 1927

UNITED STATES PATENT OFFICE

MERLIN M. JACKSON, OF SAN JOSE, CALIFORNIA, ASSIGNOR TO FRED HAMANN AND
GLEN I. LANG, BOTH OF SAN JOSE, CALIFORNIA

WASHING MACHINE

Application filed August 17, 1927. Serial No. 213,616.

It is the object of the invention to provide a simple, compact washing machine mountable upon a laundry tray and so constructed and arranged as to eliminate the necessity 5 of enclosing the impeller operating bar.

It is another object of the invention to provide a clothes washing machine of the character indicated wherein the clothes impeller may be quickly and easily thrown into 10 or out of engagement with the operating mechanism.

It is still another object of the invention to provide a clothes washer of the character indicated that will be economical to manufacture, of few parts, quickly and easily assembled, effectively lubricated without danger of leakage, light in weight, durable, and highly efficient in its practical application.

In the drawing:
20 Figure 1 is a plan view of a washing machine embodying my invention, part broken away.

Figure 2 is an enlarged section on 2—2 Figure 1.

25 Figure 3 is a section on 3—3 of Figure 2.
Figure 4 is a section on 4—4 of Figure 1, enlarged and with part broken away.

Figure 5 is an enlarged plan view of a portion of the impeller operating bar and 30 adjusting means therefor.

Fig. 6 is a section on line 6—6 of Fig. 2, and

Fig. 7 is a detail view of the means for clamping the device onto a laundry tray.

35 Referring now more particularly to the drawing, I show at 1 a plate of such a size as to lie firmly in a horizontal position on the upper edge of one section of a stationary laundry tray 2 and overlying the wall dividing 40 the two sections, the rear wall, and a portion of one end wall. The plate preferably extends the full length of the division wall of the tray and is secured thereto as well as to the back and end wall, by means 45 of any suitable clamps as indicated at 3. The portion of the plate overlying the division wall carries a clothes wringer indicated generally by the reference character 4, and has a chamber 5 formed therein intermediate 50 its length partially enclosed by an upstand-

ing annular wall 6. In the side of this wall directed toward the tray 2 is formed a bulbous portion 7 having a slot 8 formed therein a distance above the level of the bottom of the chamber as shown. The upper 55 edge of the wall 6 is provided with an outwardly extending flange 9. The remaining portion of the plate overlies the rear portion of the tray, its forward edge extending over the center of the tray and raised a distance 60 as at 10 slightly below the bottom edge of the opening or slot 8.

In the plate 1 and over the center of the tray 2 is formed an opening 11 fitted with a conical bearing member 12 on which is 65 mounted a gear 13 enclosed in a case 14. Passing through the member 12 and engaging the upper end of the conical portion 15 of gear 13 and to revolve therewith is an impeller rod 16 having a clothes impeller 70 mounted upon its lower end as at 17. Engaging the gear 13 is a rack 18 having a slot 19 formed upon the back thereof. In the slot 19 and journaled in plate 1, is a cam 20 provided with an operating handle 21. By 75 means of this cam the rack 18 may be moved into or out of engagement with the gear 13 as desired.

Mounted on the chamber 5 and in vertical axial alignment therewith is a housing 22. 80 This housing is of less diameter than the chamber 5 as shown and is provided with an outwardly extending flange 23 at its lower end adapted to rest upon the flange 9 to which it is secured by bolts 24. A depending flange 85 25 is carried by flange 23 to engage the wall 6 and form a seat or shoulder as at 26 for a bottom plate 27 as shown, the plate 27 having a bearing 28 formed therein for a shaft 29. Spaced a distance above the plate 27 is a partition 30 formed in the housing and 90 dividing it into chambers 31 and 32. This partition has an upstanding conical portion formed in its center as at 33 and in which is formed a bearing 34, for shaft 29. 95

The shaft 29 extends downwardly into chamber 5 and has an eccentric 35 mounted thereon and engaging the rack bar 36 whereby the rack 18 is reciprocated when the shaft 29 is revolved. 100

On the shaft 29 and in chamber 31, is mounted any suitable wringer operating mechanism indicated generally by the reference 37, the shaft 38 connecting the said mechanism with the wringer rolls, not shown.

On shaft 29 and in chamber 32 is a conical bearing member 39 engaging the bearing member 33 and rotating thereon as the shaft 29 rotates therein. A gear 40 is formed integral with member 39 and engages a worm gear 41. The gear 41 has a shaft 42 removably mounted therein, and an electric motor is mounted on the housing by means of a bracket 43, and a driving connection is inserted between the worm gear shaft 42 and the said motor as at 44. By means of this mechanism, the operation of the motor will revolve the shaft 29 and reciprocate the impeller as desired.

An important feature of this invention is the construction of the housing 22 and the assembling of the several parts therewith. The gear 40 and bearing member 39 may first be mounted on the shaft after which the shaft is inserted through the bearing 34 and the mechanism 37, this being followed by the plate 27. When the eccentric 35 and bar 36 are mounted on the shaft the bar 36 is passed through the slot 8 and the housing seated upon the wall 6 and secured in position.

By providing the mechanism 19, 20, 21 constant operation of the impeller when the wringer is in use is avoided.

Another important feature of the invention relates to the lubrication. As herein disclosed lubricating fluid may be placed in the chamber 32 to lubricate the bearing member 39. A very small quantity of this lubricant will work its way over the bearing and down the shaft to the eccentric, so that all parts are thoroughly lubricated, yet there is no danger of oil escaping into the tray 2.

The bracket 43 performs two important functions, it supports the motor 45 and is mounted on the plate 1 in front of the bar 36, thereby protecting it and preventing the washing from becoming entangled with it.

The construction hereinbefore set forth also permits of the mounting of a cover plate 46 on the plate 1 by means of hinges as 47. This plate may be dropped down to cover the forward portion of the tray when desired, or may be raised to uncover the same. When raised it effectually protects all of the rear of the plate 1 and the parts mounted thereon and effectually prevents clothing or articles being washed from coming in contact with them.

Still another important feature of the invention is the position of the motor 45. When the motor is mounted upon the plate 1 and between the housing 22 and the more remote edge of the plate its weight is utilized in steadyng the machine and holding it in po-

sition and less reliance may be placed upon clamping devices.

In constructing the device as above set forth the plate 1 is so proportioned that the rear edge thereof is in alignment with the rear edge of the tray upon which it is placed as at 48. This insures the impeller always being in the correct position and spaced a certain definite distance from the back of the tray, regardless of the size of said tray.

It is to be understood, of course, that while I have herein shown and described but one specific embodiment of the invention, changes in form, construction, and method of assembly and operation may be made within the scope of the appended claims.

I claim:

1. In a washing machine, a plate formed to seat on the top of a laundry tray and provided with a depressed part forming a chamber having an upstanding annular wall, said wall having a slotted portion and a horizontal flange, a housing having a horizontal flange secured to said first named flange and having a depending flange engaged within the annular wall of the chamber and a downwardly facing seat, a bottom plate engaged within said depending flange and against said seat, a partition in the housing above said plate, a shaft journaled in said bottom plate and partition, a clothes impeller rotatably carried by the plate, means to actuate the impeller having a part extending through said slot of the slotted portion, means on the shaft and disposed in said chamber to operate said actuating means, and means connected to the shaft above the partition to actuate same.

2. In a washing machine, a plate formed to seat on the top of a laundry tray and provided with a depressed part forming a chamber having an upstanding annular wall, said wall having a slotted portion, a housing secured to the wall and having a partition, a bottom plate for the housing, means to engage the bottom plate to hold same in place, a shaft journaled in said bottom plate and partition, a clothes impeller carried by the first named plate, means to actuate the shaft, and means to drive the impeller from the shaft having a part extending through said slot of the slotted portion and into the chamber.

MERLIN M. JACKSON.
